CLAIM

The ornamental design for a locker door, substantially as shown and described.

DESCRIPTION

FIG. 1 is a front perspective view of a first embodiment of a locker door according to my new design;

FIG. 2 is a top plan view thereof, the bottom view being a mirror image;

FIG. 3 is a rear elevation view thereof;

FIG. 4 is a left side edge view thereof;

FIG. 5 is a right side edge view thereof;

FIG. 6 is a front perspective view of a second embodiment of a locker door according to my design;

FIG. 7 is a top plan view thereof, the bottom view being a mirror image;

FIG. 8 is a rear elevation view thereof;

FIG. 9 is a left side edge view thereof; and,

FIG. 10 is a right side edge view thereof.

1 Claim, 2 Drawing Sheets---
